COLLAPSIBLE MILK CARTON HOLDER

Ernest R. Walker, Fort Worth, Tex., assignor to Charles E. Shriver, Fort Worth, Tex.

Application May 26, 1955, Serial No. 36,241

Term of patent 14 years

(Cl. D58—26)

Fig. 1.

Fig. 2.

Figure 1 is a perspective view of a collapsible milk carton holder embodying my new design, in operative position, and

I claim:

The ornamental design for a collapsible milk carton holder, substantially as shown.
